(57) **CLAIM**

The ornamental design for a connecting device for combustion engine, as shown and described.

DESCRIPTION

FIG. 1.1 : is a perspective view of a connecting device for a combustion engine;

FIG. 1.2 : is a front view thereof;

FIG. 1.3 : is a back view thereof;

FIG. 1.4 : is a top view thereof;

FIG. 1.5 : is a bottom view thereof;

FIG. 1.6 : is a left side view thereof

FIG. 1.7 : is a right side view thereof

FIG. 1.8 : is another perspective view thereof.
